UNITED STATES PATENT OFFICE.

MAX VON RECKLINGHAUSEN, OF NEW YORK, N. Y., ASSIGNOR TO AIR REDUCTION COMPANY, OF NEW YORK, N. Y., A CORPORATION OF NEW YORK.

APPARATUS FOR CHARGING CYLINDERS WITH OXYGEN.

1,314,773.

Specification of Letters Patent. Patented Sept. 2, 1919.

Application filed March 20, 1917. Serial No. 155,988.

To all whom it may concern:

Be it known that I, MAX VON RECKLINGHAUSEN, a German citizen, and a resident of the city of New York, county of New York, State of New York, have invented certain new and useful Improvements in Apparatus for Charging Cylinders with Oxygen, of which the following is a specification.

10 In the manufacture of oxygen in large quantities for commercial purposes the air is liquefied and the oxygen thereafter separated from the nitrogen and other gases by a process of rectification, the oxygen appearing in the form of a liquid. Heretofore it has been the practice to evaporate this oxygen and store it as a gas in large gas-holders and thereafter compress the same by a suitable compression apparatus, such as 20 a force pump, and force the same into the oxygen cylinders under the pressure or tension desired.

Generally water is used as a lubricant for the compression pump employed for compressing the oxygen gas, with the result that it not infrequently happens that a certain amount of water finds its way into the oxygen cylinders which is objectionable, particularly from the standpoint of the pur-

30 chaser.

I have conceived the idea that it would be very desirable and of very great advantage if the oxygen were taken from a tank or other receptacle in liquid form and conducted therefrom either directly or meditately to the oxygen cylinders so that the pressure of gas in the cylinders could be generated or produced by the force of expansion due to the conversion of the liquid 40 oxygen into a gas,—thereby eliminating the operation of permitting the liquid oxygen to gasify and thereafter compressing the same by means of compression apparatus of suitable construction and forcing it under 45 compression into the oxygen cylinders in which it is sent into commerce.

With this idea in mind I have conceived and designed certain apparatus well adapted for effecting the filling or charging of the 50 oxygen cylinders from tanks or receptacles of liquid oxygen and permitting or causing the force of expansion due to conversion of

the oxygen into oxygen gas to create the proper tension or compression of the oxygen in the cylinders and without the necessity 55 of a gas compression device, such as a force pump. By providing such apparatus I am enabled to bring about a substantial reduction in the cost of charging the cylinders with oxygen previously produced as a liquid 60 in well known air liquefying and oxygen separating apparatus.

In one form of apparatus employed by me I conduct the oxygen as a liquid from the point where it is collected, as for instance, at the bottom or base of a rectifying column into a tank in which the oxygen is caused to boil, that is, is evaporated and the gas thus produced as a result of the conversion of the oxygen liquid into a gas is 70 conducted through proper connections to the oxygen cylinders.

It may happen that the force of expansion exerted by the oxygen gas resulting from such evaporation will become so great 75 as to render the connections between such tanks liable to explosion, or the pressure of expansion might be or become greater than is required to fill the oxygen cylinders with oxygen gas under the usual pressure of 120 80 atmospheres.

My invention comprehends means for controlling and regulating the pressure of the oxygen gas in the connections and in the cylinders into which the same has been conducted by the said connections.

Other objects and advantages of my invention will be referred to in the detailed description thereof which follows or will be apparent from such description.

In the accompanying drawings, to which reference should be had for a clear and full understanding of my invention, I have illustrated in a more or less schematic way several modifications of construction embodying the principle of my invention, but it will be understood that changes in the details of construction may be made within the scope of the claims without departing from my invention as the same is pointed out and particularly set forth in the said claims.

In the accompanying drawings:—

Figure 1 is a top plan view showing a plurality of tanks arranged in proximity to

each other; also indicating a container for supplying liquid oxygen first to a pipe common to the said tanks and thence to any one or all of them; and also showing pipes each 5 of which is connected to the said tanks and each of the said last mentioned pipes being also shown as having connection with manifolds to which the oxygen cylinders to be filled are connected.

10 Fig. 2 is a similar view of a single tank and portions of the pipes associated therewith, all being shown somewhat enlarged.

Fig. 3 is a transverse sectional view taken on the line A—A of Fig. 2.

15 Fig. 4 is a horizontal sectional view taken on the line B—B of Fig. 3.

Fig. 5 is a horizontal sectional view taken on the line C—C of Fig. 3; and

Fig. 6 is a sectional view showing a modification of the means employed for converting the liquid oxygen into a gas.

Referring to the drawings, 1 designates a container for the reception of liquid oxygen as the same is formed or separated 25 from the nitrogen of the atmosphere and may be the base portion of the rectifying column in which the separation of the oxygen and nitrogen is effected. On the other hand the container may be any other 30 receptacle to and into which the liquid oxygen is conveyed after it has been separated from the nitrogen of the atmosphere. The oxygen which may be collected or which may be present in the container 1 may be 35 conveyed therefrom through a pipe 2 to a pipe 3 having separate pipe connections, as 4, with the respective tanks 5 and 5^a. I have illustrated six of these tanks in the drawings, but it will be understood that the 40 number may be increased or diminished as desired.

The pipe 2 is provided with a valve at 7 for controlling the passage of the liquid oxygen from the container 1 into the pipe 45 3 and the branch pipes 4 are provided with valves as at 8 for controlling the passage of the liquid oxygen from the pipe 3 to the respective tanks 5 and 5^a. It will be apparent, therefore, that any one or all of 50 the tanks 5 and 5^a may be placed in communication with the pipe 2 and through the latter with the container 1. In the construction as shown the several branch pipes 55 4 are connected to the underneath side of the said tanks. These tanks are separate and distinct from each other as is clearly shown in the drawings.

Each tank is provided with a pipe 10 which extends upwardly therefrom and 60 which is provided at its upper end with a safety valve and vent 11 of any known construction, the details of which are not shown in the drawings. Each of the tanks 5 is also provided with a pipe 12 which ex-

tends therefrom and which is connected by 65 means of branch pipes 15 and 16 with pipes 17 and 18. Passage of gas from the tanks 5 through the pipes 12 to the pipes 17 and 18 is controlled by valves at 19 and 20 in the respective branch pipes 15 and 16. Each 70 of the tanks 5^a is also provided with a pipe 12^a which extends therefrom and which is connected by branch pipes 15^a and 16^a with said pipes 17 and 18. Valves 19^a and 20^a are provided for controlling the passage of 75 gas through the branch pipes 15^a and 16^a. The two pipes 17 and 18 are common to all of the tanks, 5 and 5^a.

It is preferable that no liquid oxygen be permitted to enter either the pipe 17 or the 80 pipe 18. Any suitable means may be employed in the pipes 12 and 12^a to prevent the passage therethrough of liquid oxygen.

Generally in the employment of the apparatus the liquefied oxygen is admitted 85 from the pipe 3 only into one or more of the tanks 5, the tanks 5^a being reserved and used as safety or pressure regulating tanks. If desired, however, and if it be found to be practicable the liquefied oxygen may be delivered into one or all of the tanks 5^a as 90 well as the tanks 5.

In order that the operation of vaporization or the conversion of the liquefied oxygen in the tanks into gaseous oxygen 95 may be effected quickly and rapidly it is desirable that means be provided for directing a current of relatively warm air or other gas around said tanks. The air employed for this purpose should be free from moisture 100 and carbon dioxid in order that the surfaces of the tanks shall not become covered with ice or frozen dioxid.

The manner in which moisture and carbon dioxid are removed is immaterial but the 105 warm air employed may be taken from some portion of an air liquefying apparatus after these substances have been removed and before the air has been cooled to any substantial extent.

For economical reasons the air, after it has been employed for effecting vaporization of the liquid oxygen in the tanks or any of them and after it has been cooled in its passage around said tanks, should be conducted to the air liquefying apparatus and there liquefied and separated, if desired, into 115 its constituent parts.

For the purpose of supplying relatively warm air to the spaces surrounding the 120 tanks I have provided a couple of pipes 23 and 24 arranged in substantial parallel relation to each other. Relatively warm air is supplied to the pipe 23 and thence through branch pipes 25 to chambers or spaces 26 in 125 which the tanks are located. The direction of flow in these branch pipes 25 is controlled by means of check valves at 27. The warm

air entering a chamber 26 through a branch pipe 25 is compelled by means of a cut off plate 30 or other means to travel through the said space or chamber 26 entirely around the tank in such space or chamber and is discharged through a branch pipe 31 into the exhaust cold air pipe 24. The branch pipes 31 are also provided with check valves at 32. From the pipe 24 the air employed for vaporizing the oxygen is reconveyed to the air liquefying apparatus and is subsequently liquefied in any known manner. However, such air may be otherwise disposed of. Without the provision of some such means as that described for effecting a more rapid vaporization or boiling in the tanks the operation would proceed unnecessarily slow.

It is apparent that by properly manipulating the valves any one or all of the tanks 5 and 5^a may be connected or disconnected from the pipe 3. Likewise any one or any number of the said tanks may be connected or disconnected from either or both of the pipes 17 and 18 by manipulating and properly setting the valves 19, 19^a, 20 and 20^a.

I have provided two manifolds 40 and 41 having means as indicated at 42 and 43 whereby the said manifolds may be connected with oxygen cylinders 44 and 45 to be filled. The number of cylinders to be filled simultaneously may be varied as desired. Each of the pipes 17 and 18 is connected with each of the manifolds 40 and 41 and the pipes 17 and 18 are also connected with each other as shown in Fig. 1.

The pipe 17 is connected to the manifold 40 by means of an extension pipe 46 which is adapted to be opened and closed by means of a valve at 47. 48 designates a pipe having connection with the pipe 46 and with the manifold 41 and also with the pipe 18. The said pipe connection 48 is provided with two valves, one of which 50 is situated between its connection with the pipe 46 and with the manifold 41 and the other one of which at 51 is situated between its connection with the pipe 18 and the manifold 41.

The pipe 18 has connection through the connecting pipe 52 with the manifold 40 and also with the pipe 46 being thereby in communication with the pipe 17. The pipe connection 52 is adapted to be opened and closed by means of a valve at 55.

As already indicated or suggested the oxygen usually is delivered into the cylinders 44 and 45 under a pressure of about 120 atmospheres. It may happen that the pressure generated by the evaporation of the oxygen in one or more of the tanks 5 will and does create in the cylinders 44 or 45, as the case may be a pressure greater than 120 atmospheres and, as already suggested, the pressure may become so great as to be liable to

cause an explosion or bursting of the connections between the tanks 5 and the cylinders 44 or 45, as the case may be, or of the cylinders themselves.

In order to provide means for controlling the pressure of the gas within the pipes 17 and 18, the remaining connections, and in the cylinders 44 or 45 I purpose to employ a certain number of tanks which I have designated as 5^a as safety tanks into which ordinarily no liquefied oxygen is introduced. If the pressure resulting from the evaporation of oxygen which has been introduced into any one or more of the other tanks 5 of the series is greater than is necessary or is so great as to be liable to cause an explosion or bursting of any of the parts I open one or more of the valves 19^a or 20^a controlling the branch pipes 15^a and 16^a so as to relieve the pressure in either pipe 17 or 18, as the case may be. By properly manipulating the valves and opening up a greater or less number of the safety tanks the pressure of the gas may be regulated and controlled.

After the gas has been charged into the cylinders from one of the manifolds 40 or 41, say the cylinders 44 having connection with the manifold 40, the said cylinders 44 are removed and empty cylinders are supplied in their places. The oxygen remaining in the tanks 5 from which the oxygen has been delivered under the pressure required to the oxygen cylinders and such of the safety tanks 5^a as may have been used, is under the pressure of about 120 atmospheres. These tanks are then placed in communication with the said empty cylinders and as much of the oxygen gas as will do so is permitted to flow into the said cylinders, thereby reducing very materially the amount of oxygen in the tanks.

In this way, the amount of oxygen gas pressure which is wasted as a result of having to permit the oxygen to escape from the tanks before or as the latter are filled with liquefied oxygen is reduced to a minimum. The oxygen escaping at this low pressure may be stored and used in other ways, for instance, for purging the shipping cylinders by creating a vacuum in them first, so as to remove all impurity and then fill them with this low pressure oxygen before the same are to be attached to the manifold.

By properly manipulating the valves 47, 50, 51 and 55 the cylinders having connection with one of the manifolds, say 40, may be filled with oxygen gas to the required pressure, say 120 atmospheres, while at the same time the tanks from which oxygen has previously been taken at high pressure for filling a series of cylinders may be placed in communication with newly supplied empty cylinders and the oxygen at low pressure delivered thereto.

The construction of the tanks 5 and 5^a may be varied as desired and in Fig. 6 I have shown a modified construction of tank or perhaps it may be more accurately described as a modified construction of means for effecting evaporation of the liquefied oxygen. The construction as shown in said Fig. 6 comprises the pipe 3, the branch pipes 4, the valves 8, the pipes 17 and 18, the warm air pipe 23 and the cold exhaust pipe 24, substantially as shown in the preceding figures of the drawings. Instead of, however, using liquid oxygen receivers in the form of tanks, as shown in the preceding figures, I employ a helically coiled pipe 60 strong enough to resist the pressure resulting from the conversion of the oxygen in the said pipe from liquid to gaseous form. This pipe is surrounded by a larger helically coiled pipe 61 which produces a helical chamber or space 62 to which warm air from the pipe 23 may be delivered through a branch pipe 63. 64 designates a branch pipe leading from the upper end portion of the helically coiled pipe 61 to the cold air exhaust pipe 24 and 65 designates a pipe having connection with the upper portion of the helically coiled pipe 60 which pipe 65 is connected by means of branch pipes 66 and 67 with the pipes 17 and 18 from which the oxygen in the form of a gas is delivered through proper connections, as already described, to the cylinders to be charged with the gaseous oxygen. The pipe 65 is also provided with a couple of branch pipes 68 and 69, the former being provided at its upper end with a safety valve indicated at 70 and the latter being provided with a vent indicated at 71 for permitting air to enter the pipe 65 and also for permitting the same as well as other gases to escape therefrom as the liquid oxygen enters through the branch pipe 4.

It will be understood that there are branch pipes 4, and pipes 63, 64 and 65 for each of the tanks or, as they may be called, interchangers.

I claim:

1. The combination of means for receiving a liquefied gas, controllable means for causing evaporation of said gas, a receptacle to be charged with the evaporated gas and pressure regulating means for regulating and controlling the pressure of the gas in the said means and in the said receptacle.

2. In apparatus of the character described, the combination of receivers for receiving a liquefied gas, means for delivering said liquefied gas to any or all of the said receivers, means for causing evaporation of the said liquefied gas, one or more receptacles to be charged with the said evaporated gas and means intermediate the said receivers and the said receptacles for

regulating and controlling the pressure of the gas in the said receptacles.

3. In apparatus of the character described, the combination of a plurality of receivers for receiving liquefied oxygen, means whereby the said liquefied oxygen may be delivered to any one or all of the said receivers, means for causing evaporation of the said liquefied oxygen, a pipe having connection with the said receivers, means whereby any or all of the said receivers may be connected with the said pipe, one or more receptacles having connection with the said pipe for receiving oxygen gas therefrom and means for regulating and controlling the pressure of the oxygen within the said receptacles.

4. In apparatus of the character described, the combination of a plurality of receivers, means for delivering a liquefied gas to said receivers, means for causing evaporation of said gas, a plurality of pipes associated with the said receivers and adapted to receive evaporated gas therefrom, pressure regulating and controlling means also having connection with the said pipes, manifolds, means whereby either or both of the said pipes may be connected with the said manifolds, substantially as described.

5. In apparatus of the character described, the combination of a plurality of receivers, means for delivering a liquefied gas to said receivers, means for causing evaporation of said gas, a plurality of pipes associated with the said receivers and adapted to receive evaporated gas therefrom, pressure regulating and controlling means also having connection with the said pipes, manifolds, means whereby either or both of the said pipes may be connected with the said manifolds, and receptacles having connection with the said manifolds for receiving gas from the latter, substantially as described.

6. In apparatus of the character described, the combination of a plurality of tanks, means for delivering liquefied oxygen to certain of said tanks, means for causing evaporation of the said oxygen, a plurality of pipes each having independent connection with each of the said tanks, additional tanks each having independent connection with the said pipes and being adapted to regulate and control the pressure of the evaporated gas in the said tanks and in the said pipes and receptacles having operative connection with the said pipes and being adapted to receive the oxygen gas from the latter.

7. In apparatus of the character described, the combination of a plurality of tanks, means for delivering liquefied oxygen to certain of said tanks, means for

causing evaporation of the said oxygen, a plurality of pipes each having independent connection with each of the said tanks, additional tanks each having independent connection with the said pipes and being adapted to regulate and control the pressure of the evaporated gas in the said tanks and in the said pipes, manifolds, means whereby either or both of the said pipes may be con-

nected with the said manifolds and receptacles for receiving oxygen gas having connection with the said manifolds, substantially as described.

In testimony that I claim the foregoing as my invention I have hereunto signed my name this 14 day of March A. D. 1917.

MAX VON RECKLINGHAUSEN.
